FREIGHT CONTAINER

Benjamin F. Fitch, Greenwich, Conn.

Original application June 29, 1936, Serial No. 87,973. Divided and this application March 31, 1937, Serial No. 134,018

8 Claims. (Cl. 280—12)

This invention relates to a demountable container which may be mounted interchangeably on highway trucks or railway cars and thus transport the contained freight from source to destination. The present invention is a division of my copending application for Letters Patent, Serial No. 87,973, filed June 29, 1936. The present invention is particularly concerned with the provision of a container which may be readily slid 10 between the car and adjacent truck or platform.

The container with which this invention is particularly concerned, is one especially adapted for use in the freight-transporting system, described and claimed in my copending application, heretofore referred to. In such a system the railway cars are preferably provided with upwardly facing channels arranged in pairs, preferably extending transversely of the car, and the truck is provided with correspondingly spaced channel 20 shaped guideways preferably extending lengthwise thereof and in registration, as nearly as practicable, with those of the car during transfer of the container.

A feature of my present invention relates to the provision of such skid rails on the container to enable it to slide readily, and also to reduce the adherence of the body to the car in case of freezing during inclement weather. This provision prevents a strain on the operating motor 30 and mechanism, which moves the containers especially during the breaking of the containers loose from the car in case of such freezing.

Another feature of my invention is the provision of a container skidrail which may be economically manufactured and affixed to the container, and which skid rails will be comparatively light in weight and at the same time be capable of withstanding comparatively rough usage as, for instance, the sliding of the container between a railway car and truck, the channel guideways of which do not strictly align one with the other.

Further features and objects of the present invention will become more apparent from the following description, which refers to preferred forms of the invention illustrated in the accompanying drawing. The novel and essential features of the invention are summarized in the claims.

In the drawing, Fig. 1 is a fragmentary plan of a railway flat car or platform equipped with my transverse guide channels and illustrates a container equipped with the skid rails of the present invention as being slid thereon; Fig. 2 is a side elevation showing a container mounted

on the car; Fig. 3 is a vertical section through the car channel and body skid rail, as indicated by the line 3—3 on Fig. 2; Fig. 4 is a fragmentary plan of the rail removed (indicated by the line 4—4 on Fig. 3); Fig. 5 is an end view of the skid rail and coacting guide channel; Fig. 6 is a vertical transverse section on the line 6—6 on Fig. 3.

In Figs. 1 and 2, A indicates the railway flat car and B a demountable freight container for mounted thereon, which is also suitable for mounting on highway truck. Extending cross-wise of the car are pairs of parallel channels 10, which are adapted to receive skid rails on the underside of the bodies B. The highway truck 15 (not shown) is also equipped with a pair of parallel channels which correspond in construction and spacing to any pair of channels on the car. For a more complete description of these channels reference may be had to my copending application, heretofore referred to. In use, the truck is placed with its channels approximately 20 registering with channels 10 of the railway truck. The truck is then coupled to the railway car by means of suitable bridges, not shown, but which 25 take the form of those described and claimed in my copending application for Letters Patent, Serial No. 39,725, filed September 9, 1935, and reference may be had to such application for a detailed description of such bridges, as well as for 30 a power-operated mechanism especially adapted to transfer the containers between a truck and a railway car or shipper's platform, or vice versa.

Each skid rail is made up of an intermediate member 20 and two shoes 26 located at its opposite ends. The intermediate member is hollow, and preferably U-shaped in cross-section as indicated at Fig. 6. These U-shaped rails are outwardly flanged at their tops as shown at 21, and these flanges are riveted or otherwise secured to 40 the container body B. As shown, the flanges 21 are riveted to flanges b of suitable body bracing members through an intermediate plate b1.

As shown in Figs. 1 and 3, the intermediate portion of the skid rail is shorter than the width of 45 the body B, while the shoes at the ends of such intermediate portion project slightly beyond the body. This shoe 26 is a hollow member substantially U-shaped in cross-section and is preferably a steel casting. This casting is of the hollow 50 form shown; has an extension portion or U-shaped neck 27, sufficiently reduced to snugly occupy the channel 20 to which it is secured, as, for instance, by welding. Each shoe 26 also has flanges 28, which are secured to the container. 55

The end of each shoe is oppositely tapered, as at 29, and upwardly rounded on the under side, as at 23.

5 Beyond the channel 20 the shoe 26 has its under surface depressed with the result that the skid rail effectively supports the body by engaging the car or truck support only near the opposite ends of the skid rail.

10 The under surface 30 of the skid rail shoe just described is ground smoothly, so it may readily slide on the support. The shoe preferably rides on a liner 12, mounted on the webs 11 of the channel 10. The engaging surface of smoothly ground steel readily slides on the liner surface.

15 The extension shoes described operate also to keep the center of the body rails out of contact with the car channels, thus materially reducing the extent of surface which could make a frozen contact in the winter time. Suitable 20 drain holes 14 are provided through the base of the channels and through the corresponding floor plate of the car to prevent accumulation of liquid in the channel. The result is that the surface which has to be broken loose, in case the 25 body has been standing in the channels in freezing weather, is restricted to the comparatively small area between the engageable surface on the skid rail and the liner 12.

30 The guide channels are provided with isolated pairs of bosses 15 to co-act with the sides of the skid rail, instead of continuous engagement of channel flanges with the rails reduces the friction of the sides of the skid rail, as well as the 35 degree of adherence from freezing, and to facilitate the transfer of the container between non-aligning guideways. These bosses are more fully described and claimed in my copending application, Serial No. 87,973, heretofore referred to.

35 The tapered ends 29 of the skid shoes serve to 40 guide the body rail into position between the bosses when the body is moved horizontally to or from the railway car.

I claim:

45 1. A container having on its underside a pair of skid rails, each rail having an intermediate portion of upwardly facing channel shape and a pair of end extensions having reduced parts occupying the channel of the intermediate portion and secured thereto.

50 2. A container having on its underside a pair of skid rails, each rail having an intermediate portion U-shaped in cross-section and having end extensions in the form of shoes, each shoe having a reduced neck extending into the channel of the 55 intermediate portion and having beyond the neck a flat portion smooth on its underside and lower than the intermediate portion of the skid rail, the top of the shoe having flanges for attachment to the body and the end of the shoe being curved 60 upwardly and tapered on its sides.

3. A container having on its underside a pair of parallel skid rails, each rail having an intermediate portion U-shaped in cross-section and having end extensions in the form of shoes, each shoe being generally U-shaped in cross-section, the side wall surfaces thereof forming continuations of side wall surfaces of the intermediate portion of the rail, the bottom surface of each shoe depending below the bottom surface of the intermediate portion of the rail, each shoe having a reduced portion adapted and arranged to project into the intermediate portion of the rail and be secured thereto, and wherein the outer ends of each shoe is curved upwardly to a point substantially above the bottom surface of the 10 intermediate portion of the rail. 15

4. A container having on its underside a pair of parallel skid rails, each rail being U-shaped in cross-section, each leg of the U having adjacent its upper end outwardly extending flanges 20 for attachment of the rail to the container, shoes secured to the opposite ends of each rail, each rail having an intermediate bottom surface higher than the adjacent bottom surfaces of the shoes, the outer end of each shoe converging inwardly and its bottom extending upwardly to facilitate entrance of the rail into a guideway. 25

5. A container having on its underside a pair of parallel skid rails, each rail composed of an intermediate hollow portion and a pair of extension shoes having necks extending into the intermediate portion and having bodies depending below the intermediate portion. 30

6. A container having on its under side a pair of skid rails, each rail carrying at its end a shoe having its bottom lower than the bottom of the rail between the shoes, the shoe and rail being secured together and one of them extending into the other. 35

7. A container having on its under side a pair of skid rails composed of an intermediate portion and a pair of end shoes, each shoe being a hollow casting with a bottom portion lower than the intermediate portion, substantially upright side walls, the top portion engaging the under side 40 of the container structure, and the shoe having at its inner end a projection extending into the intermediate portion. 45

8. A container having on its under side a pair of parallel skid rails, each rail composed of an intermediate portion of sheet metal bent into a U-shape and a pair of cast steel end shoes adapted to sustain the container and providing a rubbing surface on the support, said end shoes at their tops being operatively connected to the bottom of the container and at their inner ends connected to said intermediate portion. 50 55
